J. MENEGUS.

COMBINED SASH BALANCE AND FASTENER.

APPLICATION FILED JUNE 29, 1911.

1,008,846.

Patented Nov. 14, 1911.

UNITED STATES PATENT OFFICE.

JIULIUS MENEGUS, OF NEW YORK, N. Y.

COMBINED SASH BALANCE AND FASTENER.

1,008,846.

Specification of Letters Patent. Patented Nov. 14, 1911.

Application filed June 29, 1911. Serial No. 636,061.

To all whom it may concern:

Be it known that I, JIULIUS MENEGUS, a subject of the King of Italy, residing in New York, in the borough of Queens, county of Queens, and State of New York, have invented certain new and useful Improvements in Combined Sash Balances and Fasteners, of which the following is a specification.

10 This invention relates to an improved combined sash balance and fastener which, in place of being lifted for being opened and which is closed by gravity, is automatically raised by the action of spiral springs, which 15 are wound up by the downward motion of the window, when closing the same.

In car-windows the opening of the same on releasing the locking catches is frequently connected with considerable difficulty as the 20 weight of the window has to be overcome.

The object of this invention is to produce 25 the automatic opening of the car-window by the simple pressure on a button so that the barrels of the lifting springs are released and the opening of the window greatly 30 facilitated; and for this purpose the invention consists of a car-window which is provided in both stiles with spiral lifting springs which are located in barrels or housings provided with ratchet-wheels, said 35 ratchet-wheels being engaged by suitable releasing mechanism when the window is to be opened and placed in mesh with rack-bars in the uprights of the window-casing.

35 The invention consists further in the arrangement of a pivoted lever-handle at the lower cross-bar of the car-window and mechanism between the lever handle and the ratchet-mechanism of the barrels of the lifting 40 springs for releasing the barrels when lowering the window and rewinding the lifting springs.

The invention consists further of spring-actuated mechanism for holding the ratchet-wheels of the spring-barrels in mesh with the 45 rack-bars of the window-frame and lastly of mechanism for holding the window in raised position in connection with the ratchet-mechanism of the barrels of the lifting 50 springs.

In the accompanying drawings, Figure 1 represents a front-elevation of my improved combined sash balance and fastener, with parts being broken away, Fig. 2 is a 55 vertical section through the lower inner portion of the window drawn on a larger scale

and showing one of the lifting springs for the same and the mechanism for releasing the barrels of the lifting springs for permitting the automatic lifting of the window, 60 Fig. 3 is a detail horizontal section on line 3, 3, Fig. 2, Figs. 4 and 5 are respectively a vertical transverse section on line 4, 4, Fig. 2, and a horizontal section on line 5, 5, Fig. 2, Fig. 6 is a detail of the rack-bar, showing the means for holding the car-window when in raised position, and Fig. 7 is a vertical transverse section on line 7, 7, Fig. 2.

Similar letters of reference indicate corresponding parts throughout the different 70 figures.

Referring to the drawings, *a* represents the casing and *b* the sash of a car-window. The casing *a* is provided at both sides of the sash with grooves *a*¹ in which are arranged rack-bars *b*¹. In the lower portion of the side-rails of the window-sash *b* are arranged recesses of sufficient size to permit the insertion of spiral lifting springs *e* and their barrels *e*¹. The inner ends of the lifting springs are attached to shafts *s* which are provided with square ends that are guided in recesses *f*¹ of side-plates *f*. A U-shaped keeper *f*² is guided in the recesses of the side-plates and bears on the square 85 ends of the shaft *s*. The circumference of each barrel *e*¹ is provided with a ratchet-wheel *e*² the teeth of which are held, by means of a flat spring *e*³ which presses on the rear-end of the U-shaped keeper *f*², in 90 mesh with the rack-bar *b*¹, as shown clearly in Figs. 2 and 3. The spiral springs *e* are attached at their inner ends to the shafts of the barrels and at their outer ends to the inner circumferences of the same. They are 95 of sufficient strength for counterbalancing the weight of the window-sash and for lifting the sash automatically as soon as the locking pawls *e*⁴ of the ratchet-wheels on the spring barrels are released. The locking mechanism for the spring-barrels is 100 preferably actuated so as to release the spring-barrels, by pressure on one or two push-rods *g* which are arranged on a cross-bar *g*¹ in a casing *g*² in the lower rail of the car-window, and by intermediate mechanism between the buttons and the locking pawls of the spring-barrels. The inward pressure on one of the push-rods *g* pushes a spring *g*³ which is provided with a projecting lug *g*⁴ inwardly and out of the recess of a slide-plate *g*⁵ that is guided on and acted upon 105 110

by the free ends of a flat spring g^7 , so that the spring moves the slide-plate g^5 in downward direction and produces by the engagement of pins g^8 on the same with inclined slots h^1 of two slide-plates h the laterally-shifting motion of the same. The slide-plates h are connected at their outer ends by means of rods h^2 with the lower ends of spring-actuated levers h^3 which are fulcrumed into recesses at the lower corners of the window-sash, the upper ends of said levers engaging the lower arms of the fulcrumed, elbow-shaped pawls e^4 , the upper arms of which engage the teeth on the ratchet-wheels on the barrels of the lifting springs, as shown in Fig. 2. As soon as either one of the buttons is depressed, the releasing mechanism is actuated and the locking pawls withdrawn from engagement with the ratchet-wheels on the spring-barrels, so that the lifting springs can act and raise instantly the window-sash into open position. The turning of the spring-barrels is accomplished in the direction of the arrows in Fig. 2, and produces by the intermeshing of the ratchet-wheels e^2 with the rack-bars the lifting of the sash.

The rack-bars b^1 are provided near their upper ends with arc-shaped portions b^2 which are arranged concentrically with the spring-barrels, said arc-shaped portions permitting the support of the window-sash in raised position as the ratchet-wheels are forced by the spring-actuated keepers of the spring-barrels in outward direction and into mesh with the arc-shaped portions formed in the ratchet-bars, so that a "dwell" is provided for the window-sash, when arriving in raised position under the influence of the lifting springs.

For closing the window-sash, a handle n is hinged to lugs on the front-plate of the casing of the releasing mechanism, said handle being provided with a spring n^1 that holds the handle in raised position on the casing. The handle n is provided at the lower end with a projection n^2 that enters through a slot n^3 in the front-plate and engages the lower end of the slide-plate of the releasing mechanism so as to return it into raised position into engagement with the lug on the spring-plate. During the downward motion of the sash the ratchet-wheels are first moved out of the arc-shaped portions b^2 and then in downward direction and produce, as they are in mesh with the rack-bars, the rewinding of the springs until the sash arrives in its lower or closed position when the lever-handle is released. The springs, being rewound by the downward motion of the sash, are in condition for again lifting the sash and opening the

window on depressing either one of the releasing buttons.

The advantages of my improved car-window are that the same can be opened without any effort by the automatic action of the lifting springs, and that by the downward motion of the sash, which is assisted by the gravity of the same, the lifting springs are rewound and placed in condition for the next lifting and opening of the sash.

Having thus described my invention, I claim as new and desire to secure by Letters Patent:

1. The combination, with the frame of a car-window provided with rack-bars, of a sash provided with lifting springs, one in each jamb of the same, spring-actuated barrels for said springs, means for guiding the barrels toward the racks, ratchet-wheels on said barrels, locking pawls for said barrels, and a releasing mechanism for the ratchet-wheels of the lifting springs, said releasing mechanism consisting of push-rods in the lower rail of the sash, and intermediate mechanism between the push-rods and pawls for actuating the latter and releasing the spring-barrels.

2. In a car-window, the combination of a window-frame provided with rack-bars having inwardly-bent portions or dwells at their upper ends, a window-sash, spring-barrels located in the lower side-portions of the jambs of the sash, ratchet-wheels on said spring-barrels, means for guiding the barrels toward the racks, springs for holding the ratchet-wheels of the spring-barrels in mesh with the racks, locking means for said barrels and a releasing mechanism for said spring-barrels.

3. In a car-window, the combination, with a window-frame provided with rack-bars in its sides, of a window-sash, spring-barrels in the lower portions of the jambs of the window-sash, ratchet-wheels on said spring-barrels meshing with said rack-bars, locking means for said barrels, a releasing mechanism for said spring-barrels, a fulcrumed and spring-actuated handle on the lower rail of the sash, and means for operating the releasing mechanism so as to withdraw the locking means from the ratchet-wheels of the spring-barrels and permit the winding of the springs on the downward or return movement of the sash.

In testimony, that I claim the foregoing as my invention, I have signed my name in presence of two subscribing witnesses.

JIULIUS MENEGUS.
